COSMETIC HOLDER

Albert Gelardin, New York, N. Y.

Application August 16, 1941, Serial No. 407,177

2 Claims. (CL 206—56)

This invention relates to new and useful improvements in cosmetic holders and more particularly to holders for lipsticks, eyebrow pencils and the like.

The primary object of the present invention is a cosmetic holder, all the parts of which are wholly composed of plastic material.

Another object of the invention is a cosmetic holder so constructed and designed as to permit all of the parts to be made wholly of plastic material.

It has heretofore been proposed to provide a cosmetic holder in which the carrier for the cosmetic is advanced by the relative rotation of two slotted members but such cosmetic holders of the prior art had, because of their design and construction, to be made entirely of metal or, in a few cases, partly of metal and partly of plastic material.

The present invention therefore relates to features of a cosmetic holder whereby all of the component parts thereof may be wholly made of plastic material.

These and other objects of the invention and the means for their attainment will be more apparent from the following detailed description taken in connection with the accompanying drawing illustrating one embodiment by which the invention may be realized and in which:

Figure 1 is a view in perspective showing a cosmetic holder in the form of a lipstick or eyebrow pencil;

Figure 2 is a longitudinal sectional view showing the cosmetic holder in closed position;

Figure 3 is an exploded view showing the component parts of the lipstick holder of this invention, partly in section and partly in elevation;

Figure 4 is an enlarged view showing the carrier for the lipstick or eyebrow pencil; and

Figure 5 is a plan view of the carrier of Figure 4.

Referring to the drawing in which similar parts are indicated by identical reference numerals, the preferred embodiment of my invention embodies a substantially two-piece construction comprising an inner sleeve and an outer sleeve cooperating therewith together with a separate cover member. The inner sleeve 7 is of tubular form and of constant diameter, the lower end of which is closed by a disc-like bottom 8 providing a peripheral flange 9 extending outwardly beyond the cylindrical wall 7 and turned upwardly on its periphery as a wall 31. The tubular portion of this inner sleeve is provided with

a longitudinal slot 11 terminating above the bottom of the sleeve, as at 13. This member may be easily formed as a unitary member of plastic material as, for instance, by an injection process.

5 The carrier, as illustrated in Figure 4, comprises a cup-shaped member, the cylindrical wall 15 and perforated bottom 17 of which are formed of plastic material. On the outer surface of the cylindrical wall of the carrier is formed a lug 19, preferably cylindrical and of a length to pass through the slot 11 in the inner sleeve 7 and enter a helical groove 21 in an intermediate member 23 next to be described. This carrier is readily formed of plastic material in a simple manner, as will be understood.

The intermediate sleeve is formed at its lower end with a peripheral flange 25. The upper end of the intermediate sleeve is bent inwardly as a flange 27 defining an aperture 29 substantially 20 equal to the aperture formed by the inner sleeve 7 and so as to conceal the inner sleeve and form a passage for the lipstick or eyebrow pencil 30 (Figure 2) during its protrusion and in protruded position. The cosmetic 30 is of a diameter less 25 than the outer diameter of the carrier to avoid contact with the inner sleeve 7. On its inner surface, the intermediate sleeve is formed with a helical groove 21 commencing in the plane of the bottom surface of the sleeve and extending 30 upwardly to a point proximate the open mouth 29 thereof. Again this member may be readily formed of plastic material as by an injection process.

In assembly, the carrier 15 is inserted in the intermediate sleeve 23 with the lug or pin 19 in the groove 21 therein and the sleeve 23 is then telescoped over the inner sleeve 7 so that the lug 19 on the carrier 15 enters the groove 11 in the inner sleeve and the flange 25 on the intermediate sleeve 23 rests upon the flange 9 on the inner sleeve 7.

The two flanges are readily secured together by the cylindrical wall 31 which is of greater height than the height of the flange 25 on the intermediate sleeve, and the plastic wall 31 of the inner sleeve is readily turned inwardly, as at 35 (Figure 2) over the flange 25 on the intermediate sleeve 23 to irremovably retain the two sleeves in relatively fixed position while permitting relative rotation therebetween.

A removable cover is provided comprising a cylindrical portion 33 and an end closure portion 36 integral therewith which is conveniently formed with a flat inner surface 37 recessed at 55 the center, as at 39, to conform somewhat to the

shape of an end of a lipstick or eyebrow pencil. The cylindrical wall 33 is of a length to permit the removable cover to be slipped over the intermediate sleeve 23 and rest upon the inturned edge 35 of the inner sleeve 7.

The removable cover being of plastic material, readily lends itself to ornamentation. As shown, the peripheral surface of the cylindrical portion of the removable cover is fluted, as at 41, as is an annular area 43 on the upper end thereof surrounding a disc-like raised portion 45.

To retain the lipstick or eyebrow pencil in position in the carrier, tongues 47 are, if desired, provided which are formed as dihedral angles with a sharp edge 49 sloping downwardly from the wall 15 of the cup to the inner sharp edge 51 of the anchoring prongs and sloping downwardly and outwardly from the upper edge 49 to the bottom 53 of the cup-shaped carrier. Again the sides 55 of the prongs are angularly related and slope from the sharp edge 51 outwardly from one another to the wall of the cup. The opposed edges 51 of the anchoring prongs may conveniently be notched, the notch having a horizontal upper surface 57 and an inclined inner surface 59 so that a lipstick, for instance, pressed down into the carrier will have portions thereof readily entering the notch to anchor the lipstick against displacement. The prongs are readily formed integrally with the carrier in the one operation while the notch is readily formed by inserting a rotating cutting tool axially with the cup, as will be understood.

It will thus be seen that a lipstick holder has been provided which is composed of a minimum number of parts, all of which are readily formed of plastic material in simple operations and which requires only a single operation to secure the component parts of a holder, as distinguished from the removable cover, into a non-separable unit. The lipstick holder so constructed presents a graceful and pleasing appearance and is capable of ornamentation to provide an attractive product.

Various modifications will occur to those skilled in the art in the particular plastic composition used and the method of forming the plastic and no limitation is intended by the phraseology of

the foregoing description or illustrations in the accompanying drawing except as indicated in the appended claims.

What is claimed is:

5. 1. A two-piece cosmetic holder comprising a unitary, relatively thick-walled outer sleeve formed with an internal helical groove and a peripheral flange at its lower end, a thick-walled longitudinally slotted, unitary inner sleeve movably fitted within the outer sleeve, said inner sleeve having a bottom and a peripheral flange in the plane of its bottom and extending beyond the periphery of the lower end of the outer sleeve, a rim portion of the said bottom flange being 10 turned over and on the flange on the outer sleeve to retain the said sleeves together in axially rotatable relation, and a carrier disposed within the inner sleeve, said carrier having a peripheral lug extending through the slot in the inner sleeve into the helical groove of the outer sleeve, whereby manual rotation of the bottom of the inner sleeve will effect relative rotation of the respective sleeves with concomitant travel of the carrier.
- 15 2. A two-piece cosmetic holder comprising a unitary, relatively thick-walled outer sleeve formed with an internal helical groove and a peripheral flange at its lower end, together with an inturned annular top flange, a thick-walled longitudinally slotted, unitary inner sleeve movably fitted within the outer sleeve, said inner sleeve having a bottom and a peripheral flange in the plane of its bottom and extending beyond the periphery of the lower end of the outer sleeve, 20 a rim portion of the said bottom flange being turned over and on the flange on the outer sleeve to retain the said sleeves together in axially rotatable relation, and a carrier disposed within the inner sleeve, and substantially co-diametrical with the aperture of the said annular top flange, said carrier having a peripheral lug extending through the slot in the inner sleeve into the helical groove of the outer sleeve, whereby manual rotation of the bottom of the inner sleeve 25 will effect relative rotation of the respective sleeves with concomitant travel of the carrier.

ALBERT GELARDIN.
